UNITED STATES PATENT OFFICE.

FRED L. MACKENZIE, OF BEVERLY, AND GEORGE GODDU, OF WINCHESTER, MASSACHUSETTS, ASSIGNEES TO UNITED SHOE MACHINERY CORPORATION, OF PATERSON, NEW JERSEY, A CORPORATION OF NEW JERSEY.

FASTENING-INSERTING MACHINE.

Application filed October 8, 1919. Serial No. 329,342.

To all whom it may concern:

Be it known that we, FRED L. MACKENZIE and GEORGE GODDU, citizens of the United States, and residents of Beverly, in the county of Essex and Commonwealth of Massachusetts, and Winchester, in the county of Middlesex and Commonwealth of Massachusetts, respectively, have invented certain Improvements in Fastening-Inserting Machines, of which the following description, in connection with the accompanying drawings, is a specification, like reference characters on the drawings indicating like parts in the several figures.

15 This invention relates to fastening inserting machines.

As heretofore constructed machines for inserting fastenings having a plurality of points or attaching prongs have not infrequently comprised means for making in the work perforations designed to receive the prongs of each fastening as it is driven. Ordinarily an awl mechanism is provided for the purpose described. In machines 25 which insert single pronged fastenings the awl mechanism in addition to making perforations in the work is utilized almost universally in feeding the work, the arrangement being such that the awl is caused to pierce the work and to move laterally 30 progressing the work over the work support until the perforation is in exact alinement with the fastening driver. Probably no difficulty would arise in operating an awl 35 carrier carrying a plurality of awls in the manner described for the single awl were it not for the fact that it is often necessary or desirable to turn the work during work feeding and fastening inserting operations 40 to insert fastenings along a curved path, as for instance, in driving fastenings into the soles of boots and shoes.

It is an object of this invention to provide an improved awl mechanism for feeding the work along a straight or a curved path and for making a plurality of perforations in the work, in each cycle of operations, for the reception of a plurality of fastenings or of a fastening having a plurality of prongs.

50 In the illustrative construction means is provided for operating the awl mechanism in such manner that but one awl pierces the work preliminary to the feeding movement thereof. As shown the means for operating

the awls to cause them to perforate the work 55 is individual for each awl, the operating means for all the awls having an element in common, and automatic means is provided for preventing the operation of all but one awl at the initial work piercing position of 60 the latter, the arrangement being such that the work may be fed along either a straight or a curved path at the will of the operator.

In one aspect the invention comprises an awl mechanism normally operative to force a 65 plurality of awls into the work and means independent of the awl operating means and automatically operative to control said mechanism so that but one awl is in the work at a predetermined point in the cycle 70 of operations.

In another aspect the invention resides in a plurality of awls constructed and arranged to penetrate an equal distance part way 75 through a piece of work to make perforations in the work for the prongs of fastenings and so operated that but one awl is caused to pierce the work preliminary to a work feeding operation.

Conveniently the automatic means for controlling the awl mechanism is under the control of the operator so that the feeding of the work may be discontinued when desired. This is a marked advantage particularly 80 when it becomes necessary or desirable to set a fastening in a certain location in the work or a succession of fastenings in such relation to each other or to the work that the work feeding mechanism cannot be advantageously utilized for the purpose of locating the work in proper position for the fastening or fastenings.

From another viewpoint the invention comprises an awl feed mechanism and automatically operating mechanism under the 95 control of the operator for discontinuing the feed of the work without interrupting the effective operation of other work operating instrumentalities.

In still another aspect the invention 100 resides in an awl mechanism for feeding the work and for making successively perforations in the work directly at the point of fastening insertion and means for discontinuing the feed of the work by the awl without interrupting the operations of making perforations in the work and driving fastenings therein.

In the construction illustrated in the drawings the fastening receiving and guiding member is adapted to receive a multi-pronged fastening and is mounted on a movable member so that it may be withdrawn to permit a plurality of awls to move to position over the work and directly beneath the driver, so as to insure that the perforations made by the awls operated while in the described position will receive the prongs of the fastenings. Preferably also the fastening guiding member is mounted adjustably upon the reciprocable member with the object in view of making a fine adjustment of the former with respect to the adjacent end of the raceway.

Other objects and advantages of the invention and other combinations of parts will be described in connection with the following detailed specification and will be pointed out in the claims.

In the drawings:

Fig. 1 is a front view of the illustrative fastening inserting machine;

Fig. 2 is a side view of the machine shown in Fig. 1;

Fig. 3 is a sectional detail view taken along the line 3—3 of Fig. 1;

Fig. 4 is a detail view of a portion of the awl mechanism looking toward the front of the machine in Fig. 1;

Fig. 5 is a view of the parts shown in Fig. 4 looking from the right in the latter figure; and

Fig. 6 is a detail view in perspective of the combined driver guide and fastening guide nozzle.

In the illustrative machine the hopper or magazine 10 is designed to receive plural-pronged fastenings in mass, means being provided for transferring the fastenings to the bar raceway 12 down which they slide to driving position. The said means comprises preferably a disk 14 having a plurality of arms 16, the disk being mounted on a shaft 18 for rotation in one direction so that the arms are caused to dip into and pass through the mass of fastenings whereby certain of the latter will be engaged by the curved edge of the arm and carried upwardly away from the mass to be later deposited on the raceway. From an inspection of Fig. 1 it will be clear that as the disk turns the fastenings will slide from the curved edge 20 of one arm while straddling the said edge, to the straight edge 22 of the succeeding arm. In order to permit the fastenings to slide from the arm on to the bar raceway 12 the disk is given an intermittent rotary motion of such a character that the disk has an interval of rest with the straight edge of the fastening delivering arm in alignment with the raceway. The means for operating the disk in the manner described comprises preferably a plate 24

secured to the shaft 18 and having a plurality of radially arranged slots 26 and between each pair of slots a concaved edge portion 28. Mounted in the bracket 30 extending from the head of the machine is a shaft 32 driven continuously by means comprising gears 34 and 36, the former being mounted on a shaft 38 arranged to be driven by connections to the main shaft 40, provision being made for connecting and disconnecting the shaft 38 from its driving connections by means not shown but arranged to be controlled by a rod 42 having a handle 44 adapted for manipulation by the operative. Fixedly attached to the shaft 32 is a crank plate 46 having an arm 48 carrying at its outer end a roller 50 designed to enter successively the radial slots 26 in the plate 24. The crank plate 46 also has a peripheral portion arranged to slidably engage successively with the concaved edges 28 of the plate 24. The arrangement is such that as the crank plate 46 rotates the roller 50 is caused to engage one of the radial slots and thus turn the plate 24, the curved portion of the crank plate in cooperation with the concaved edge 28 of the plate 24 serving to hold the plate stationary at certain intervals in such position that the straight edge of an arm on disk 14 is in alignment with the bar raceway 12.

As the fastenings, which in the present instance are in the form of staples, slide down the bar raceway the foremost ones are engaged by a retaining member 54 pivoted at 56 in the raceway cover and yieldingly held in fastening retaining position by means of a spring such as that shown at 58. Means is provided for separating one fastening at a time from those in the raceway and shoving it into the combined driver guide and fastening guiding member 60 which, at the time of the operation is located in abutting relation to the end of the raceway. In the illustrative construction the means for separating the endmost fastening and positioning it as described comprises the fastening separating member 62 having a forked end 64 arranged to straddle the end of the fastening retaining member 54, which projects beyond the end of the raceway cover, in such manner as to engage the ends of the cross bar of the staple fastening to shove the same from the end of the raceway. Means is provided for causing an oscillatory sliding movement of the member 62 so that the lower end of said member may successively engage the fastenings as described, the said means consisting in the illustrative construction of an arm 66 secured to a shaft 68 mounted in the cover of the raceway, the said arm having pivoted thereto at its outer end the fastening separator 62. Mounted on the shaft 68 is an arm 70 adjustably connected to move with the shaft by means of a

pin and slot connection with a projecting member 72 rigidly secured to the shaft. Rocking movement is imparted to the shaft 68 by means of a lever 74 pivoted at 76 in the frame of the machine and carrying a roller 78 held constantly in contact with the face of the cam 80 by means of a spring 82. The lower end of the lever 74 is pivotally connected to a block 84 slidable in the end 10 of the arm 70. It will be evident that oscillation of the lever 74 causes a rocking motion of the shaft 68 whereby the fastening separator is oscillated to engage the fastenings successively and shove them from 15 the end of the raceway.

The mechanism for driving the fastenings comprises a driver 86 carried at the lower end of the driver bar 88 which is lifted by a cam on the main shaft and operated in its 20 driving stroke by means of the spring actuated arm 90, though obviously the driver bar may be actuated positively in both directions by cam means on the shaft according to a well-known construction. Since it 25 is desired to feed the work automatically and to prepare perforations in the work into which the prongs of the fastenings are inserted, the fastening guiding nozzle is made movable so that it may be displaced and 30 thus permit the awl mechanism to position the work with the perforations directly in the line of drive. In the illustrative construction the awl moves along from the right with its point engaged in the work while the 35 combined driver guide and nozzle is displaced rearwardly, the latter as shown being mounted on a sliding bar 92 by means comprising a slot and bolt 94 by which adjustment of the guide member 60 may be made. 40 Means is provided for reciprocating the slide 92 in properly timed relation to the other mechanisms comprising, in the construction shown, a lever 96 pivoted at 98 and carrying at its upper end a roll movable along the cam 45 slot 100 in the cam 102 on the main shaft. The lower end of the lever 96 is provided with a segment rack 104 having teeth in mesh with teeth on the rear end of the slide 92. 50 The awl mechanism in the illustrative construction comprises a slide 106 reciprocable in a guideway 108 by means comprising a lever 110 pivoted at 112 on the bracket 114 extending from the head of the machine and 55 carrying at its upper end a roll 116 movable along the cam slot 118. The throw of the lever 114 may be determined by proper adjustment of its fulcrum 112 in the slot 120 in the bracket 114. Extending laterally from 60 the slide 106 is a stud 122 enclosed by an eccentric sleeve 124 carried by the lower end of the lever 110 whereby straight line reciprocations of the slide are caused by the rocking of the lever 110 without any binding action at the point of connection. Preferably

a wear plate 123 is mounted in the upper part of the guideway above the slide 106 and is made adjustable by set screws or bolts 125. In the preferred construction the forward end of the slide 106 is enlarged to provide a 70 casing or housing 126 within which is slidably mounted a carrier 128 enclosing two awl bars 130 slidable with respect to the carrier and provided at their lower ends with awls 132. The operative connections between the carrier 128 and the awl bars comprise an abutment 134 on the carrier arranged to engage beneath the lower ends of the awl bars at the point 136 so that upon 75 upward movement of the carrier the awl bars will be positively retracted in a direction away from the work. The said operative connections comprise also a pair of latches 138 pivoted on the carrier at 140 adjacent the upper end of the carrier and acted 80 upon by springs 142 to cause the lower end 144 of each latch to engage in a notch 146 in the corresponding awl bar, the construction being such that downward movement of the carrier 128 causes also downward movement of the awl bars, that is when the latches are in operative position, to force the awls into the work. Clearly, if either one or both 85 of the latches are so tipped as to remove the end 144 from the notch in its respective awl bar, no operative stroke of the awl bar or bars would follow a downward movement of the carrier and thus either or both awls, as the case may be, would fail to penetrate the work. Means is provided for positively 90 moving the awl carrier 128 toward and from the work comprising preferably a lever 148 (Fig. 2) pivoted at 150 in the frame of the machine and carrying a roll which moves in the cam slot 152 in the cam 102 on the 95 main shaft of the machine, the said lever being operatively connected to the awl carrier by means of intermeshing teeth on the segmental rack 154 and the straight rack 156 on the carrier. The cam slot 152 is so constructed that the piercing movement of the awl preliminary to the feeding movement thereof is not so great as the piercing movement which results in the formation of perforations to receive the fastening or fastenings. Since the carrier moves laterally with 100 respect to the lever during reciprocation of the awl to feed the work the intermeshing teeth are made to extend laterally a distance sufficient to permit of the lateral movement 105 of said carrier without possibility of disengagement of the teeth on the respective racks. 110

One of the contemplated uses of the fastening inserting machine disclosed is that 115 of inserting two-pronged fastenings in the soles of shoes by a mechanism which not only inserts the fastening but provides means whereby the work may be intermittently fed to proper position for the inser- 120

tion of each fastening. In the illustrative construction there is provided means for perforating the work for both prongs of the double pronged fastening, the said means comprising awls, one of which is utilized to feed the work, it being impracticable to use both awls in the feeding of the work since the shoe must be turned in passing from one side around the toe to the other side of the shoe. Hence, the construction is such that one awl is caused to pierce the work and to move it into feeding direction and this operation is followed by such an operation of the awls as will provide perforations in the work for both prongs of the fastening. In the illustrative construction one of the awls is automatically thrown out of operation as the awls return to initial piercing position preliminary to the feeding operation. As shown, a throw-out member 158 (Fig. 3) is mounted on the bracket or stationary guideway for the slide in such position as to be contacted by the arm 160 of the front latch, the said arm riding up over the member 158 in such manner as to lift the end 144 of the latch out of the notch 146 in the front awl bar. Immediately thereafter the carrier 128 is depressed through the operation of the lever 148 to force the rear awl into the shoe sole. Subsequently, the slide 106 together with the carrier 128 are moved to the left (in Fig. 1) to cause the awl to feed the work, the arrangement being such that the awl places the perforation directly below the end of the driver 86, the guide member 60 being at that time in rearward position. As soon as the work has been thus located by the awl the work support, not shown, is operated to clamp the work against the work abutment 162 and simultaneously both awl bars are lifted including the one which has penetrated the work and then immediately depressed to cause both awls to penetrate the work simultaneously and to an equal depth. This is a feature of importance since the two-pronged fastenings would frequently be improperly driven if the perforations were of unequal depth as this would result in a difference in the resistance encountered by the two prongs of the fastening. The awls are then withdrawn and moved laterally and the combined driver guide and fastening guiding nozzle moves forwardly to receive a fastening which is later driven by the driver into the perforations made by the awls. Subsequently the awl pierces the work preliminary to another work feeding operation during which the work is released by a slight depression of the work support.

Occasionally it is desired to omit the feeding operation of the work and insert fastenings in positions determined by the operator. For this purpose both of the catches

138 are automatically released from connection with their respective awl bars; that is their lower ends 144 are moved out of the notches 146 in the awl bars when the slide moves to the right in Fig. 1; that is, to the initial work piercing position when the work is to be fed. The means in the construction shown for throwing the feeding awl out of operation comprises a member 164 (Fig. 3) which may be lifted to operative, dotted-line position upon turning the cylindrical member 166, the latter being connected to the throw-out member 164 by an eccentric stud 168. For the convenience of the operator in turning the member 166 a handle 170 is provided integral with or securely attached to a member 166. For holding the cylindrical member 166 in position wherein the throw-out 164 is operative, a leaf spring 172 is arranged to contact with a flat surface on a connecting portion between the handle and the cylindrical member. From an inspection of Fig. 1 it will be seen that two such flat surfaces are provided for holding the member 166 in either desired location. With both of the throw-out members 158 and 164 in operative position both of the awl bars will be disconnected operatively from the awl carrier 128 and hence neither awl will be forced into the work prior to the movement of the awls toward the driver. However, when the awls have reached a position beneath the driver they will be reciprocated and caused to pierce the work, thus providing perforations in which the points of the fastening will be received.

Under certain conditions it may be desirable to use both awls in feeding the work as when feeding work of considerable width in a straight line, the entrance of both awls tending so to control the work as to maintain a straight line feed. The machine is readily adapted for such a manner of operation simply by removing the throw-out member 158 which, as shown in Fig. 3, is secured in place by a set screw 176, the latter making it possible to remove and replace the throw-out member as desired. With the throw-out member 158 removed or otherwise rendered inoperative and the throw-out 164 in inoperative position as shown in Fig. 3 in full lines, both awls will be caused to enter the work upon downward movement of the carrier 128 preliminary to movement of the carrier and slide to the left in Fig. 1. When the work has been moved to proper position both awls are lifted and then given an operative stroke to make perforations for the fastening.

Having described my invention, what I claim as new and desire to secure by Letters Patent of the United States is:

1. In a machine of the class described, two awls, means for forcing one of the awls

into the work to feed the same, means for withdrawing said awl at the termination of the feeding movement, and means subsequently operative for forcing both awls into 5 the work preliminary to a fastening inserting operation.

2. In a machine of the class described, two awls, awl bars for carrying said awls, means operative to move the awl bars toward the work, means for automatically disconnecting one of the awl bars from said means so that only one awl is forced into the work preliminary to the feeding operation on the work, and means for moving the 10 awls in the direction of feed to feed the work.

3. In a machine of the class described, two awls, means normally operative to force one of the awls into the work preliminary 20 to the feeding operation, and manually controllable means arranged to be automatically operative to disconnect said awl from its operating means so that neither awl is caused to penetrate the work preliminary 25 to lateral movement of the awl thus eliminating the feeding of the work.

4. In a machine of the class described, an awl, means for moving the awl to cause it to penetrate the work and feed the same preliminary to a fastening inserting operation, a second awl arranged in parallel relation to the first mentioned awl, means for lifting both awls subsequently to the feeding of the work and for driving them simultaneously 35 into the work to make perforations therein.

5. In a machine of the class described, an awl, means for forcing the awl into the work and for moving it laterally so that the work is fed by one awl only, a second awl, 40 means for operatively connecting the awls to each other, and means for forcing the awls simultaneously into the work to provide perforations of equal depth therein.

6. In a machine of the class described, 45 awls, awl bars for carrying said awls independently movable with respect to each other, means for causing one awl to penetrate the work prior to the other to feed the work, and a single means for operating both awl bars as a unit to cause both awls to penetrate the work preliminary to a fastening inserting operation.

7. In a machine of the class described, 55 means for driving fastenings comprising a fastening driver and a stationary guide therefor, a plurality of awls to provide perforations for the fastenings, means for inserting one awl only into the work to effect a feed of the work, and means to cause insertion of the awls an equal depth into the work preliminary to a fastening inserting operation.

8. In a machine of the class described, 60 two awls of the same length, awl bars carrying said awls, a lever to move one awl to

cause it to penetrate the work, and means to cause said awl to feed the work before the other awl is operated to engage the work, said lever being operative to force both awls into the work preliminary to a fastening inserting operation.

9. In a machine of the class described, a plurality of awls, awl bars for carrying said awls, a lever and connecting means between the lever and awl bars for operating the bars independently of each other to force the awls at different times into the work so that one awl may be utilized to feed the work, and means for causing the awls to make perforations in the work preliminary to a 70 fastening inserting operation.

10. In a machine of the class described, awls of equal lengths, awl bars carrying said awls, a single lever for operating the awl bars, said parts being constructed and arranged to cause one awl to enter the work in advance of the other, and means to cause the awl first entering the work to feed the same.

11. In a machine of the class described, a plurality of awls, awl bars for carrying said awls movably independently of each other, means for reciprocating the awls toward and from the work, and means operating automatically to disconnect all but one 90 awl bar from the operating means so that the awl bar which remains connected may be utilized to feed the work, and means for moving the last mentioned awl bar in the direction of feed to feed the work.

12. In a machine of the class described, a plurality of awls, awl bars for carrying the awls movable independently of each other, means for moving the awl bars simultaneously toward and from the work, and means under the control of the operator for automatically disconnecting one or more of the awl bars from said operating means.

13. In a machine of the class described, fastening means comprising a driver for inserting two-pronged fastenings, a combined driver guide and fastening guiding nozzle movable into and out of position beneath the driver, means for feeding a fastening into said fastening guiding nozzle after the latter 110 has come to rest under the driver, and means comprising two awls movable to a position in alinement with the driver for piercing the work directly beneath the driver, thus ensuring that the perforations will be in exact 115 position to receive both prongs of the fastenings.

14. In a fastening inserting machine, means for driving a two-pronged fastening, means for perforating the work for both 120 prongs of the fastening operated to make perforations of the same depth, said means comprising a plurality of awls, and means automatically operative to cause one awl to penetrate the work and feed the same into 125 130

proper position for the insertion of a fastening.

15. In a machine of the class described, a plurality of awls, awl bars carrying said awls, means for moving the awl bars in directions at right angles to each other to cause one awl to enter the work and feed the same laterally, means for operating both awls simultaneously in one plane to cause them to make a plurality of perforations in the work preliminary to a fastening inserting operation, and means under the control of the operator for rendering said awl ineffective to feed the work.
15. 16. In a machine of the class described, a plurality of awls, awl bars for carrying said awls, a slide for moving said bars back and forth in the direction of feed of the work, means for causing one of the awls to penetrate the work so that the work will be fed on reciprocation of said slide, means for operating both awls to make a plurality of perforations in the work preliminary to fastening inserting operations, and means controllable by the slide for rendering said awl inoperative to feed the work.

17. In a machine of the class described, a plurality of awls, awl bars for carrying said awls, a slide in which the awl bars are independently movable, means for reciprocating the slide in the direction of feed of the work, means for automatically disconnecting one of the awls from its operating means, means for forcing the other awl into the work to feed the work during the reciprocation of the slide, and means for operating both awls to perforate the work preliminary to a fastening inserting operation.

18. In a machine for inserting fastenings into work, means comprising an awl for operating on the work to feed the same, and means under the control of the operator for automatically discontinuing the feed of the work without interrupting the insertion of fastenings.

19. In a machine of the class described, an awl, means normally operative to move the awl to pierce the work, and means under the control of the operator for automatically disconnecting said awl from said means for one or for a plurality of fastening inserting operations so that the awl is not forced into the work to cause a feeding of the work, said first-mentioned means being operative to perforate the work prior to a fastening inserting operation.

20. In a machine of the class described, an awl, means normally operative to force the awl into the work preliminary to the feeding operation, and manually controllable means arranged to be automatically operative to disconnect said awl from its operating means for one or for a plurality of cycles of the machine so that the awl is not caused to penetrate the work preliminary to lateral

movement of the awl thus eliminating the feeding of the work by the machine.

21. In a machine of the class described, a plurality of awls, means for moving one awl only to cause it to penetrate the work and feed the same preliminary to a fastening inserting operation, and means for lifting both awls subsequently to the feeding of the work and for driving them into the work to make perforations therein. 75

22. In a machine of the class described, a plurality of awls, means for operating the awls to make perforations in the work, and means independent of the operating means and automatically operative to control said means so that but one awl enters the work at a predetermined point in the cycle of operations. 80

23. In a machine of the class described, awls, awl bars for carrying said awls independently movable with respect to each other, a single member for causing penetrating movement of the awls, locking members for operatively connecting the awl bars to said member, means for causing one awl to penetrate the work prior to the other to feed the work, and means comprising said single member arranged to operate subsequently to the feeding of the work to cause both awls to penetrate the work preliminary to a 95 fastening inserting operation.

24. In a machine of the class described, a driver for fastenings, means for operating the driver, the construction and arrangement being such that the driver is held against lateral movement, two awls, means for inserting one awl only into the work and for effecting a feed of the work, and means to cause simultaneous insertion of both awls an equal distance into the work preliminary to a fastening inserting operation. 100

25. In a machine of the class described, a fastening driver, an awl mechanism operable for making successively perforations in the work at a point directly in line with the driver and for feeding the work, and means for discontinuing the feed of the work without interrupting the operations of perforating the work and driving fastenings into the perforations. 110

26. In a machine of the class described, a fastening driver, awl mechanism for feeding the work and for perforating the work while said mechanism is in line with the driver, and means under the control of the operator for automatically stopping the feed of the work by the awl mechanism without interrupting the operation of driving fastenings into the perforations in the work. 120

27. In a machine of the class described, fastening inserting mechanism comprising a fastening driver, an awl for feeding the work and movable into alinement with the driver and operable while in such position for making perforations in the work in 130

which fastenings can be inserted, and means for stopping the feed of the work by the awl mechanism without interfering with the making of perforations for the reception of 5 fastenings.

28. In a machine of the class described, a plurality of awls one of which is normally operative to pierce the work to feed the same and place the perforation in the line of 10 fastening insertion, said awls being operable to provide perforations in the work into which fastenings may be inserted, and means for preventing the piercing of the work which normally takes place preliminary to 15 a feeding operation whereby the feeding of the work is discontinued without otherwise interrupting the operation of providing perforations for said fastenings.

29. In a machine of the class described, 20 awl mechanism comprising an awl for piercing and feeding the work, means for operating the awl to pierce the work comprising a readily operable means for locking the awl to its operating means, and means for 25 automatically releasing the awl from the locking means, so that the awl does not pierce the work to feed the same.

30. In a machine for driving two-pronged fastenings, a fastening driver, a raceway, a 30 member for receiving fastenings from the end of the raceway and holding them one at a time for the action of the driver, an awl for feeding the work, two awls, including the first-mentioned awl, movable into 35 position in alignment with the driver and operable while in such position to form two perforations for the double-pronged fastening, a reciprocable member for carrying said first-mentioned member, and means for 40 adjustably securing the receiving member on the reciprocable member so that the former may be adjusted with respect to the end of the raceway.

31. In a machine for driving multi-pronged fastenings, a fastening driver, a 45 member for receiving and guiding the fastenings during driving operations, the said member being movable into and out of position beneath the driver, and a plurality of awls movable into alignment with the driver and operable while in such position to form perforations for the multi-pronged fastenings so as to ensure that the 50 perforations will be located accurately to receive the prongs of the fastenings.

32. In a machine for driving multi-pronged fastenings, a fastening driver, a member for receiving fastenings and holding them one at a time for the action of 60 the driver, an awl for feeding the work, and a plurality of awls movable into position in alignment with the driver and operable while in such position to make perforations for the fastenings thus ensuring that

the perforations are so located as to receive 65 the prongs of the fastenings.

33. In a machine of the class described, a fastening driver, a member for receiving fastenings and holding them one at a time for the action of the driver, a plurality of 70 awls operative to pierce the work for feeding the same, and means for operating the awls when they have reached a position in alignment with the driver to make perforations for the reception of the fastenings. 75

34. In a machine of the class described, a fastening driver, a raceway, a member for receiving fastenings from the end of the raceway and holding them one at a time for the action of the driver, a plurality of 80 awls for feeding the work, and means for operating the awls subsequently to the feeding operation to provide a plurality of perforations into which fastenings may be 85 driven by said driver.

35. In a machine of the class described, means for driving fastenings comprising a fastening driver and a stationary guide therefor, and means comprising a plurality of 90 awls operative to feed the work in a straight line beneath the fastening driving means and for making perforations in the work for the reception of the fastenings.

36. In a machine of the class described, a work positioning abutment, a tool for 95 operating on the work, means comprising an awl for operating on the work to feed the same, and means under the control of the operator for automatically discontinuing the feed of the work without interrupting the operation of the tool upon work 100 pressed against said abutment.

37. In a machine of the class described, means for operating on work comprising a tool and a work support, means comprising 105 an awl for feeding the work, and means under the control of the operator for discontinuing the feed of the work without interrupting the operation of the first mentioned means. 110

38. In a machine of the class described, a raceway for fastenings, a fastening guiding member for receiving the fastenings one at a time from the end of the raceway, a reciprocable bar upon which the guiding 115 member is mounted for movement out of and into position in alignment with the end of the raceway, and means for adjustably connecting the guiding member to its supporting bar. 120

39. In a machine for providing perforations for fastenings to be driven part way only through the thickness of the material being operated on, an awl, means for forcing the awl into the work and for moving it laterally so that the work is fed by the awl, a second awl, and means for forcing the awls simultaneously into the work to 125

provide perforations of equal depth therein for the reception of the fastenings.

40. In a machine for providing perforations for fastenings to be driven part way only through the thickness of the material being operated on, a plurality of awls, means for forcing one of the awls into the work and for moving it laterally so that

the work is fed by the awl, and means for forcing the awls simultaneously into the work to provide perforations of equal depth therein for the reception of the fastenings.

In testimony whereof we have signed our names to this specification.

FRED L. MACKENZIE.

GEORGE GODDU.
